UNITED STATES PATENT OFFICE

2,498,468

APPARATUS FOR ELIMINATING DUST
AND FUMESRonald Webster, Evanston, and Daniel H. Petty,
Skokie, Ill., assignors to The Hydro-Blast Corporation, Chicago, Ill., a corporation of Illinois

Application January 24, 1946, Serial No. 643,189

4 Claims. (Cl. 261—116)

1

This invention relates to method of and apparatus for eliminating dust and fumes and more particularly to the elimination of dust and fumes during shake-out of castings in foundries.

The shaking out of castings in foundry practice has long been a troublesome and unpleasant operation, particularly in the case of large castings which cannot be handled in a closed room and which require the use of heavy overhead cranes or hoists for handling. In castings of this sort, when the cope is removed from the drag a blast of hot fumes rises from the casting and from the exposed molding sand in the mold. This blast, in itself objectionable, picks up and carries with it particles of dust such as fine, heated particles of sand and the like from the mold. The fumes and dust forming the blast disperse themselves over the entire foundry causing an uncomfortable and hazardous condition for workmen in the foundry and producing a great deal of undesirable dirt.

It is one of the objects of the present invention to provide a method of and apparatus for overcoming these difficulties in the shaking out of castings.

Another object is to provide a method of and apparatus for eliminating fumes and dust whatever the source thereof.

Still another object is to provide a method of eliminating fumes and dust in a foundry shake-out operation in which the use of cranes or hoists to handle the casting or the mold parts is not interfered with.

Still another object is to provide apparatus for eliminating fumes and dust from a space confined on two sides and open at its top and ends so that easy access may be had to materials in the space.

A further object is to provide a method of and apparatus for eliminating fumes and dust in which the fumes, dust and surrounding air are entrained by high velocity water jets and are carried thereby to a point of disposal. Preferably the arrangement is such that spaced water jets form in effect an air curtain to confine and carry away the dust and fumes.

The above and other objects and advantages of the invention will be more readily apparent from the following description when read in connection with the accompanying drawings, in which—

Figure 1 is a diagrammatic prospective view of one form of apparatus embodying the invention for use in foundry shake-out operations;

Figure 2 is a diagrammatic end section of the apparatus; and

Figure 3 is a diagrammatic transverse sectional view through the jets indicating the direction of air movement.

The apparatus, as shown, is adapted to be used 60

2

on a foundry floor or the like in that portion of the foundry where castings of a relatively large size are to be removed from molds. As shown, the apparatus comprises a pair of spaced vertical walls 10 and 11 which may be of any desired length and height to provide the necessary space to accommodate the castings and molds. As shown, the wall 11 is slightly shorter vertically than the wall 10 for a purpose to appear later.

10 The floor area between the walls is preferably formed by an open grating 12 through which sand shaken from the molds may fall into a pit 13. The sand may be removed from the pit in any desired manner as, for example, by conventional conveyor mechanism, not shown.

15 The wall 10 carries at its upper portion a series of nozzles 14 supplied with water under high pressure on the order of approximately one thousand to fifteen hundred pounds per square inch from a header 15. The nozzles 14 are spaced horizontally along the upper edge of the wall 10 and are arranged to direct horizontal jets at an extremely high velocity across the top of the space and over the upper edge of the wall 11. The 20 nozzles are preferably so constructed as to produce tight streams or jets, as indicated at 16 which travel at high velocity horizontally across the top of the space without breaking up into sprays.

25 30 When water is discharging through the nozzles, the jets will produce a vortical flow of the surrounding air inwardly toward the jets and along in the direction of jet travel. For good results the jets should be parallel and spaced sufficiently far apart so that they will not interfere with each other while being close enough so that the vortical flows around adjacent jets overlap. We have found that for jets with a capacity of about 30 gal. per minute a satisfactory spacing 35 is from 20 to 30 inches. This condition is indicated in Figure 3 showing three jets with arrows indicating the direction of air flow around them. From this figure it will be seen that adjacent jets produce vortical flows in opposite directions and that the flows overlap to provide a substantially 40 continuous air curtain.

45 In operation it has been found that dust and fumes are drawn into the jets by the vortical air circulation and are carried by the jets away from the shake-out space. During this operation the dust and fumes are wetted out or absorbed by the water so that the area around the shake-out space is kept clean and free from fumes at all times.

50 55 The water of the jets and material entrained thereby is collected by a baffle 17 spaced back of the wall 11 and extending above the top of the wall, as shown. Preferably, the upper edge of the baffle 17 is curved forward so that the jets will strike it at a flat angle to minimize splash-

ing. The water from the jets and entrained air, dust and fumes will be directed downward through the space 18 between the baffle and the wall 11 to provide a distinct circulation away from the shake-out space. The baffle 17 is preferably spaced above the floor to leave an open passage thereunder through which air and gaseous material may flow. The water may flow through a screen or grating 19 forming the floor under the baffle and be conducted away to waste or for reuse.

The wall 11 effectively prevents direct return of air or gaseous material flowing through the space 18 to the shake-out space. In order to conduct such air and gaseous material away, a back wall 21 is provided spaced back of the baffle 17 to form a passage 22 through which the air, fumes and the like may flow. The passage 22 may discharge into the open foundry space or may be connected to discharge out-of-doors, if desired. It has been found that in many cases discharge of this air into the foundry space is not objectionable since the dust and a large portion of the fumes coming from the casting and the mold will be carried away with the water and will not rise through the passage 22.

In the installation illustrated, relatively large castings and molds are adapted to be handled. For this purpose, an overhead track 23 is provided on which a hoist 24 may slide. The hoist 24 operates a chain 25 adapted to be connected to a casting, a mold or the like to raise it and move it horizontally into and out of the space. As shown in Figure 2, the chain 25 is connected through a conventional hook and bail mechanism to the cope 26 of a mold. The cope is shown resting on a drag 21 to form a complete mold in which the casting is poured.

With the present construction, it will be seen that the chain 25 may extend down into the shake-out space so that the hoist mechanism can be utilized to raise the cope from the drag without interfering with the action of the jets 16. Since the hoist may be controlled from a remote point, it is not necessary for any workman to enter the shake-out space during a shake-out operation so that the entire shake-out operation can be performed with a minimum of labor and with no discomfort. We have found that operation of the jets will effectively entrain substantially all of the dust and fumes created during the shake-out and will effectively remove such dust and fumes from the shake-out space and prevent them from spreading throughout the foundry space. It will be noted that since air entrained by the jets is conducted away from the shake-out space a constant flow of air into the space from the open ends thereof occurs so that there is no tendency for the dust or fumes to diffuse horizontally through the foundry.

While the invention has been illustrated and described in connection with one particular form of apparatus, it will be understood that this apparatus is illustrative only and is not intended to be a definition of the scope of the invention, reference being had for this purpose to the appended claims.

What is claimed is:

1. Apparatus for eliminating dust and fumes during shake-out of castings comprising a pair of spaced parallel vertical walls defining a space having an open top and a series of nozzles carried by one wall and spaced along the top edge of the wall adjacent the top thereof to direct high velocity water jets substantially in a horizontal plane across the top of the space and over the top of the other wall.

5 2. Apparatus for eliminating dust and fumes during shake-out of castings comprising a pair of spaced parallel vertical walls defining a space having an open top, a series of nozzles carried by the top portion of one wall and spaced along the top edge of the wall to direct high velocity water jets substantially in a horizontal plane over the space and over the other wall, and a baffle spaced back of and extending above the other wall to collect the water and material entrained thereby and means providing a free outlet from the space between the baffle and the other wall for air entrained by the jets.

10 3. Apparatus for eliminating dust and fumes during shake-out of castings comprising a pair of spaced parallel vertical walls defining a space having an open top, a series of nozzles carried by the top portion of one wall and spaced along the top edge of the wall to direct high velocity water jets substantially in a horizontal plane over the space and over the other wall, and a baffle spaced back of and extending above the other wall to collect the water and material entrained thereby, the baffle being formed to provide an outlet for the water and entrained air and other material remote from the space whereby it is prevented from returning directly to the space.

15 4. Apparatus for eliminating dust and fumes during shake-out of castings comprising a pair of spaced parallel vertical walls defining a space having an open top, a series of nozzles carried by the top portion of one wall and spaced along the top edge of the wall to direct high velocity water jets substantially in a horizontal plane over the space and over the other wall, a baffle spaced back of and extending above the other wall to collect the water and material entrained thereby and a vertically extending back wall spaced back of the baffle, the baffle being formed to provide communication between the spaces in back and in front of it to form passages for conducting away air and gas entrained by the jets.
